ATTORNEY

UNITED STATES PATENT OFFICE.

PHILIP GOULD, OF PHILADELPHIA, PENNSYLVANIA.

DESIGN FOR A PUMP MEMBER.

SPECIFICATION forming part of Design No. 34,796, dated July 16, 1901.

Application filed May 14, 1901. Serial No. 60,248. Term of patent 7 years.

To all whom it may concern:

Be it known that I, PHILIP GOULD, a citizen of the United States of America, residing in the city and county of Philadelphia, in the 5 State of Pennsylvania, have invented and produced a new and original Design for Pump Members, of which the following is a specification, reference being had to the accompanying drawings, forming part thereof.

Figure 1 is a side elevation of a pump member, showing my new design. Fig. 2 is an elevation at right angles to Fig. 1. Fig. 3 is a plan thereof.

My design consists in the form or configuration of a pump member.

The leading features of the design are the outwardly-extending tubes a b at the foot of the cylinder A, the tube a' depending from

the tube a and the nipper-like portion b' rising from the tube b . On the tubes a b , in 20 line with their respective portions a' and b' , are semispherical protuberances a^2 b^2 . At the foot of the cylinder is an encircling band c with a depending lug c' , and at the top of said cylinder is an ornamental head d . 25

I claim—

The design for a pump member, substantially as herein shown and described.

In testimony whereof I have hereunto affixed my signature in the presence of two subscribing witnesses.

PHILIP GOULD.

Witnesses:

ANDREW V. GROUPE,
JOHN R. NOLAN.
